UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.
KILN-CAR WITH ADJUSTABLE WORK-SUPPORT.

1,371,321.

Specification of Letters Patent. Patented Mar. 15, 1921.

Application filed April 20, 1920. Serial No. 375,270.

To all whom it may concern:

Be it known that I, PAUL A. MEEHAN, citizen of the United States, and resident of New Castle, in the county of Lawrence and 5 State of Pennsylvania, have invented certain new and useful Improvements in Kiln-Cars with Adjustable Work-Supports, of which the following is a specification.

The general object of my present invention is to provide improved means for transporting goods through continuous tunnel kilns. More specifically the object of my invention is to provide goods transporting means for the purpose specified with simple 15 and effective means for moving the goods on the goods transporting means as the latter moves through the kiln, so as to equalize the heat absorption by different portions of the goods.

20 The invention was primarily devised for use in vulcanizing tires but can advantageously be used in the treatment of many kinds of goods.

The various features of novelty which 25 characterize my invention are pointed out with particularity in the claims annexed to and forming a part of this specification. For a better understanding of the invention, however, and the advantages possessed by 30 it reference should be had to the accompanying drawings and descriptive matter in which I have illustrated and described preferred forms of apparatus embodying my invention.

35 Of the drawings:

Figure 1 is an elevation of a portion of a tunnel kiln with one form of my improved goods transporting device therein.

Fig. 2 is a transverse section on the line 40 2-2 of Fig. 1.

Fig. 3 is a plan view of a modified form of goods transporting device; and

Fig. 4 is a section on the line 4-4 of Fig. 3.

45 In Figs. 1 and 2 of the drawings, I have illustrated the use of my invention in connection with continuous vulcanizing apparatus comprising a tunnel kiln R with track rails S for the cars A which carry the articles 50 to be vulcanized through the kiln, and having combustion chambers T for heating the kiln located at the sides of the pathway for the goods. The kiln illustrated is of the well known Dressler type as shown, for example,

by the patents of Conrad Dressler 1023628 55 and 1170428, but it is to be understood that the invention is not limited to use in any particular type of tunnel kiln.

The goods carrying car A shown in Figs. 1 and 2 comprises a body portion A, wheels B, and axles C, the latter being mounted in bearings A¹ carried by the car body. The car body A is provided at its opposite sides with uprising standards or brackets A² in the upper ends of which are journaled 60 a shaft D. The latter carries spiders E on which are detachably mounted the articles to be transported through the kiln. As shown these articles consist of the heavy metallic molds P in which vehicle tires are vulcanized. Provisions are made for rotating the shaft D, and thereby the tire molds and enclosed tires, as the car A moves along the track rails S. The provisions shown for this purpose comprise a pair of roller supports F journaled, one on each of the brackets A², and forming supports for rollers D¹ secured to the ends of the shaft D. The latter has its end portions received between bifurcations A³ in which the upper end of 65 each bracket A² terminates. Secured to the shaft for each roll F is a sprocket gear G. Each gear G is connected by a sprocket chain H to a corresponding sprocket gear C¹ carried by one of the car axles C. 70

With the described construction as the car A moves through the kiln, the supporting wheels F for the shaft D, and thereby the latter, are correspondingly rotated. The rotation of the shaft D revolves the tire 75 molds P carried by the shaft. This tends to equalize the heat absorption by the molds P when, as may sometimes happen, the temperature in the upper portion of the kiln chamber is higher than the temperature in 80 the lower portion P. The shaft D with the tire molds supporting it may be lifted bodily off the brackets A² when the removal of the molds is desired.

It will be understood of course that many 100 different arrangements may be made for automatically rotating, or otherwise moving goods carried on a kiln car, relatively to the latter as the car is moved through the kiln. For instance, it may be desirable to rotate 105 the goods about a vertical axis instead of a horizontal axis, in cases where the character of the kiln is such, that differences in tem-

perature may exist between the sides of the kiln chamber and the center of the latter. One form of apparatus for accomplishing this is shown in Figs. 3 and 4. The kiln cars shown in Figs. 3 and 4 comprise a car body AA and a goods carrying device I mounted therein to revolve about a vertical axis. As shown the goods carrying member I rests upon balls or rollers J held in an annular runway A⁰ formed on the car body AA. The member I has a depending shaft portion I² carrying pulley wheels I³. A cable belt HA connects the pulley wheels I³ with pulley wheels C¹⁰ secured to the car axles C so that as the car is moved along its supporting track rails the goods supporting member I is rotated. As shown the car body is formed with a refractory superstructure A¹⁰, and the goods carrying member I comprises a refractory upper portion I¹ of cylindrical form received in a cylindrical opening formed in the refractory car portion A¹⁰. The goods may be mounted directly on the upper end of the revolving portion I, but as shown, a stand member DA is seated on the portion I¹, and is provided with spiders EA on which tire molds similar to those shown in Figs. 1 and 2 or other articles to be treated in the kiln may be mounted.

With the construction shown in Figs. 3 and 4 the roller bearing for the goods supporting member and the gearing connecting the latter to the car axle are protected against the high temperature in the upper portion of the kiln chamber by the refractory car portions A¹⁰ and I¹ so that this form of my invention is adapted for use with relatively high kiln temperatures, such

as are employed for example in metal annealing substantially higher than those commonly employed in vulcanizing.

While in accordance with the provisions of the statutes I have illustrated and described the best forms of my invention now known to me, it will be apparent to those skilled in the art that changes may be made in the form of the apparatus disclosed without departing from the spirit of my invention as set forth in the appended claims and that certain features of my invention may sometimes be used to advantage without a corresponding use of other features.

Having now described my invention, what I claim as new, and desire to secure by Letters Patent, is:

1. The combination with a tunnel kiln of a car for moving goods through the kiln and goods supporting means mounted on said car and adapted to move the goods relative to the car as the latter is moved through the kiln.

2. A car for transporting goods through a tunnel kiln comprising in combination a car body, a rotatable goods supporting member journaled on the car body, and means actuated by the car movement for rotating said member as the car moves.

3. A car for moving goods through a tunnel kiln comprising in combination a car body, supporting wheels therefor, and a revoluble goods supporting member journaled on the car body and geared to the car wheels to rotate with the latter.

Signed at New Castle in the county of Lawrence and State of Penna. this 10th day of April A. D. 1920.

PAUL A. MEEHAN.
